UNITED STATES PATENT OFFICE.

EDWARD E. CLAUSSEN, OF HARTFORD, CONNECTICUT.

PULP BOTTLE.

1,328,317.

Specification of Letters Patent. Patented Jan. 20, 1920.

Application filed July 18, 1918. Serial No. 245,525.

To all whom it may concern:

Be it known that I, EDWARD E. CLAUSSEN, a citizen of the United States, residing at Hartford, in the county of Hartford and 5 State of Connecticut, have invented certain new and useful Improvements in Pulp Bottles, of which the following is a specification.

This invention relates to pulp bottles, the 10 object of the invention being the production of an article of this character which can be easily and quickly made, which possesses extreme strength, and which is capable of containing liquid or other substances. As a 15 matter of fact the bottle is primarily intended to contain a beverage, for illustration, beer or milk.

In the drawings accompanying and forming part of the present specification I show 20 in detail a form of embodiment of the invention which to enable those skilled in the art to practise the same will be set forth fully in the following description. I do not necessarily restrict myself to this particular 25 disclosure; I may depart therefrom in several respects within the scope of the invention defined by the claims following said description.

Referring to said drawings:

30 Figure 1 is an elevation of a half of the bottle in primary condition.

Fig. 2 is a cross section on the line 2—2 of Fig. 1, looking in the direction of the arrow.

35 Fig. 3 is a view corresponding to Fig. 1 of the finished bottle half.

Fig. 4 is a cross section on the line 4—4 of Fig. 3, looking in the direction of the arrow.

40 Fig. 5 is an elevation of the finished bottle.

Fig. 6 is a top plan view of the same.

Fig. 7 is another elevation of the bottle taken at right angles from Fig. 5.

45 Fig. 8 is a bottom plan view of the finished bottle.

Like characters refer to like parts throughout the several views.

The bottle comprises preferably sections, for instance two complemental halves as 2.

50 Fig. 1 shows this half or section at a preliminary point in its production, while Fig. 3 illustrates the same at a later stage in the proceeding. The section 2 (a duplicate of its companion) comprises a body portion 3 having a bottom portion 4 ordinarily integral with the body portion, the tapered por-

tion 5 rising from the body portion. Preferably extending along the sides and bottom of the section 2 is a fin or bead as 6. Initially (Figs. 1 and 2) this fin or bead is 60 practically a little thicker than the intermediate portion of said section, this intermediate portion being that part of the bottle section which is surrounded by the two lateral and bottom end fins 6. This structure is 65 made in a mold or through the intervention of suitable molding or equivalent means.

After the section 2 is produced, all of it except the marginal fins 6, is by compression or with the aid of suitable molding means, 70 densified or compressed as indicated at 8 in Fig. 4, the marginal fin or body 6 after the primary action being left in its original condition. Obviously the densification of that part of the pulp mass within or surrounded 75 by the two lateral and end fins 6 produces between the fins 6 and the main portion 8, the channel or rear series of channels 9 as clearly shown in said Fig. 4. This particular view and Fig. 3 which is an elevation of 80 it, is illustrative of a section before it is united with a complemental section. The inner face of the portion 2 is flat as denoted by 10. The portion 2 is brought into relation with a similar portion, the several flat 85 faces 10 being placed against each other preferably in absolute registration. The beads 6 are then cohesively united by pressure through the intervention of suitable molding means to produce a bottle like that 90 denoted by 11 in Figs. 5 to 8 inclusive. This bottle it will be seen, has flanges 12 extending along the same from opposite sides and across the bottom, these flanges 12 being secured by pressing together the two sets of 95 beads 6. The pressure will be such that the cross section of an external bead is practically the same as the thickness of the bottle. Obviously these flanges 12 materially strengthen the bottle.

100 Each section 2 of the body of the bottle has on its bottom beads or tongues 13 at right angles to the bottom portions of the fins or beads 6 as shown best in Fig. 4. The inner end portions of these beads or 105 tongues 13 are cohesively united when the face portions of the marginal beads 6 are connected together. The result is that there is produced on the bottom of the bottle as shown best in Fig. 8 a cruciform beaded part 110 preferably flat on its under side and upon which the bottle can rest or be supported

and thus maintain the bottle in an upright condition. I should state that in forming the body of the bottle as distinguished from the bottom thereof, the pressure necessary to get the requisite thickness of the body indicated best in Fig. 4, is from the inside toward the outside of the section or half. In the case of reducing the stock on the bottom of the section 2, the pressure is applied upwardly or as it might otherwise be stated, from the outside toward the inside; in fact exactly opposite to that applied in the formation of the body. It will be clear that the pressure applied at the top of the section is downward, and this pressure is of such nature as to secure in the external part of the neck, the annular channel in which may be sprung the so-called crown cap. It is not always necessary to use such a closure, because one of an entirely different nature may be provided to seal, when necessary, the contents of the bottle.

There may be cases where I prefer to waterproof, for instance by paraffin, the inside and the outside of the bottle. I may also impress upon the bottle while in a mold through the use of a suitable die or dies, an inscription denoting the contents of the bottle and similar indicia. There may be cases, of course, where this may not be necessary, the facts being indicated by printing or by the use of a hand stamp. While the bottom of the bottle is preferably integral with the sections or halves thereof, this may not be necessary in all cases.

It will be evident that when external pressures are applied to the half or section 2 to densify the stock at the ends thereof, the length of this section is appreciably short-

ened. In fact Fig. 3 illustrates the section or half after the necessary end pressures have been applied. It will be clear that when the two sections or halves are brought together their adhering faces are flat, the inner portions of the flat faces being along the inner edges of the sections, while the outer portions are along the beads 6. The beads are actually pressed together and cohere in a thoroughly substantial manner.

What I claim is:

1. A pulp bottle having two halves, each provided with a marginal bead, the marginal beads being compressed together.
2. A pulp bottle comprising two halves, each half having a marginal bead, the marginal beads of the halves being compressed together and being initially of greater cross sectional extent than the intermediate portions of the respective halves.
3. A pulp bottle in sections, each section having a marginal bead along its sides and bottom, the beads being compressed together throughout the complete depth and width of the bottle.
4. A pulp bottle having two halves, each half having a marginal bead along its sides and bottom, the marginal beads being compressed together, the bottom also having beads at right angles to the other beads and the end portions of which are compressed together.

In testimony whereof I affix my signature in the presence of two witnesses.

EDWARD E. CLAUSSEN.
